UNITED STATES PATENT OFFICE.

JOHN F. GRACE, OF KEARNY, NEW JERSEY, ASSIGNOR TO WORTHINGTON PUMP AND MACHINERY CORPORATION, OF NEW YORK, N. Y., A CORPORATION OF VIRGINIA.

EXPANSION JOINT FOR TURBINE AND CONDENSER CONNECTIONS.

Application filed July 5, 1924. Serial No. 724,536.

This invention relates to improvements in expansion joints and especially to expansion joints for coupling turbine exhaust connections to condenser steam inlets.

The object of the invention is to provide a cheap, simple, and efficient expansion joint adapted to compensate not only for all ordinary movement of the connected parts but also any abnormal expansion, such as may occur in the condenser upon excessive heating and expansion thereof due to stoppage of the circulating pump or from any other cause, and improved coupling means therefor in which all the locking and adjustments are made from the same side of the expansion joint, so that access to only one side of the exhaust connection is necessary for applying and adjusting the joint.

In present day turbine and condenser unit installations the turbine is normally supported by a concrete foundation in which the turbine exhaust connection and steam inlet are coupled together by an expansion joint. In small unit installations having small connections it is practicable to allow sufficient space between the exhaust connection and foundation for installation and adjustment of the expansion joint from outside the vacuum space, and in such cases this arrangement is preferred, as entrance to the connection is not necessary and adjustment may be made during the operation of the turbine and condenser. Any increase in the size of the foundation because of this space involves so little foundation expense as to be of little or no consequence and, in fact, the foundation in such small units is usually of such size as to require no addition to provide for this space. In large unit installations with large connections, however, the concrete foundation is so large that for economy it must come up so close to the exhaust connection between the turbine and condenser that it is impractical to apply an expansion joint from the exterior of the vacuum space. To leave a space for this purpose about the turbine exhaust connection would result in a relatively large increase in the size of the foundation and large waste of concrete. In large unit installations, therefore, the expansion joint preferably

will be applied and adjusted from within the vacuum space.

For a full understanding of the invention a preferred embodiment thereof will now be described in detail in connection with the accompanying drawing forming a part of this specification and the features forming the invention then specifically pointed out in the claims.

In the drawing,—

Figure 1 is a side elevation partly in section, of a joint, the locking and adjusting means accessible from outside the exhaust connection;

Figure 2 is a section on the line 2—2 of Figure 1;

Figure 3 is a top plan view of a detail;

Figure 4 is a section on line 4—4 of Figure 1, and

Figure 5 is a view similar to Figure 1, showing a construction with the parts reversed for access inside the exhaust connection.

Referring to the drawing, the expansion joint, by way of illustration, is shown as joining the exhaust connection A of a steam turbine to the steam inlet B of a condenser provided, respectively, with flanges A' and B', which are external in the construction shown in Figures 1 to 4 and internal in the construction shown in Figure 5. To allow the required expansion and contraction of these parts due to temperature changes produced by the exhaust steam and otherwise, there is secured between the parts A and B a flexible member or ring 10 of any suitable flexible and resilient material, such as soft rubber, and of any desired form, but preferably an annulus having at its opposite ends suitable heads or enlargements 11, 12 preferably cylindrical in shape. This annulus is shown as cylindrical for use with a round exhaust connection, but it will be understood that the annulus may be oblong or of other form, depending on the form of exhaust connection used.

The flexible member 10 may be secured in any suitable manner but a preferred support therefor comprises supporting rings 13, 14 of suitable shape and preferably divided into a plurality of sections, having exterior

flanges 15, 16 secured respectively to the flanges A' and B' by bolts 1. The rings 13, 14 extend within the opposite ends of the flexible member 10 and are provided with 5 suitably shaped depressions 2 to receive the respective heads 11, 12 of flexible member 10, which are secured therein by a clamping ring 3 suitably recessed to receive the heads 11, 12 and secured to the supporting 10 rings 13, 14 by bolts 4. The clamping ring 3 is preferably made in sections. The division of the supporting and clamping rings into sections aids in adjustment of member 10 for sealing the vacuum space. As shown, 15 rings 13, 14 are divided into four sections and rings 3 into eight sections, but this may be varied, depending somewhat upon the size of the exhaust connection.

In order to assure that the clamps 3 shall 20 always assume the correct position relative to the rings 13, 14 and provide a bearing for its clamping action, I preferably provide a machined joint between the clamp 3 and its ring 13 or 14, as the case may be, comprising 25 an offset portion or lug 5 seating within an annular recess 6 formed in the ring 13 or 14, the lug 5 and recess 6 being suitably machined for exact fitting.

In connecting the parts the supporting 30 rings 13, 14 will first be loosely mounted on the flanges A', B' by partially tightening the bolts 1 and the flexible member 10 will then be placed in position with the heads 11, 12 outside the supporting rings 13, 14, and 35 within the depressions 2, and clamping rings 3 locked thereagainst by tightening the bolts 4. The rings formed by the heads 11, 12, preferably will be stretched somewhat when in position on the rings 13, 14, to aid in securing a tight joint. The rings 13, 14 will 40 now be drawn tightly against their respective flanges A', B' by tightening up bolts 1. The width of the flexible web of member 10 between the heads 11, 12 is preferably such 45 that it will be slightly stretched when this operation is completed, so that during the operation of the turbine and its condenser the normal expansion of the parts will allow the flexible member 10 to assume its normal 50 unstretched condition.

It will be understood that various changes 55 may be made in the construction and arrangement of parts shown and described while still retaining the invention as defined by the claims.

What is claimed is:

1. In an expansion joint, the combination 60 with two spaced hollow members, of a supporting ring secured to each hollow member, a resilient member overlapping the supporting rings, a head at each end of the resilient member, the supporting rings each being recessed to receive one of the heads, a recessed 65 clamping ring engaging each of the heads, bolts operable from one side of the joint for

drawing the clamping rings and supporting rings together to secure the ends of the resilient member, and means operable from the same side of the joint for tensioning the resilient member whereby the resilient member will tend to assume its normal unstretched condition upon the expansion of the parts. 70

2. In an expansion joint, the combination 75 with two spaced hollow members, of a supporting ring secured to each hollow member, a resilient annular member overlapping the supporting rings, a head at each end of the resilient member, the supporting rings each being recessed to receive one of the heads, a recessed clamping ring engaging each of the heads and operable from one side of the joint, and bolts operable from the same side of the joint for drawing the clamping rings and supporting rings together 80 to secure the ends of the resilient member. 85

3. In an expansion joint, the combination 90 with a plurality of hollow members, of a resilient annular member overlapping the hollow members, a head at each end of the resilient member, each of said hollow members being recessed to receive one of the heads; a sectional recessed clamping ring 95 engaging each of said heads, and bolts operable from outside the joint for clamping the heads between the sectional clamping rings and the hollow members.

4. In an expansion joint, the combination 100 with two spaced hollow members, of a sectional supporting ring secured to each hollow member, a resilient annular member overlapping the sectional supporting rings, a head at each end of the resilient member, the supporting rings each being recessed to 105 receive one of the heads, a sectional recessed clamping ring engaging each of said heads, and bolts operable from outside the joint for clamping the heads between the sectional clamping rings and the sectional supporting 110 rings.

5. In an expansion joint, the combination 115 with two hollow members having external flanges, of a sectional externally flanged supporting ring secured to each hollow member by bolts passing through the juxtaposed flanges, a resilient annular member overlapping the supporting rings, a head at each end of the resilient member, the supporting rings each being exteriorly recessed to receive one of the heads, a sectional 120 recessed clamping ring engaging each of the heads, bolts operable from outside the joint for drawing the clamping rings and supporting rings together to secure the ends of the resilient member, an annular lug on each clamping ring, and an annular recess in each supporting ring for said lug. 125

6. In an expansion joint, the combination 130 with two spaced hollow members having

flanges, of a flanged sectional supporting ring secured to each hollow member by bolts passing through the juxtaposed flanges, a resilient member overlapping the supporting rings, a sectional clamping ring cooperat-
5 ing with each supporting ring for securing the ends of the resilient member, an annu-

lar lug on each clamping ring, and an annular recess for said lug in each supporting ring.

In testimony whereof, I have hereunto set my hand.

JOHN F. GRACE.
